UNITED STATES PATENT OFFICE.

HERMANN A. KLEMM, OF NEW YORK, N. Y.

ADJUSTABLE TRIMMING ATTACHMENT FOR SEWING-MACHINES.

SPECIFICATION forming part of Letters Patent No. 693,657, dated February 18, 1902.

Application filed October 2, 1901. Serial No. 77,290. (No model.)

To all whom it may concern:

Be it known that I, HERMANN A. KLEMM, a citizen of the United States of America, and a resident of New York city, county and State 5 of New York, have invented certain new and useful Improvements in Adjustable Trimming Attachments for Sewing-Machines, of which the following is a specification.

My invention relates to overedge sewing- 10 machines having trimming attachments adjustable forward and backward relatively to the needle for varying the widths of the margins outside of the line of stitches and also having a stitch - controlling finger of the 15 presser - foot governing the tension of the loops around the edge of the fabric; and my invention consists of the presser-foot carrying such finger mounted adjustably on the presser-bar and so connected with the adjustable cutter-carrying stock that the presser 20 is automatically adjustable along with the cutters to maintain constant uniform relations of the controlling-finger and the adjustable cutters, whereby the proper relation of the 25 presser for best effects is maintained however the cutters may be shifted, as hereinafter described, reference being made to the accompanying drawings, in which—

Figure 1 is an end elevation of part of the 30 head of the needle-bar, presser-bar, and cutter - attachment - supporting head and the parts carried thereby, with a transverse section of the main shaft. Fig. 2 is a side elevation of the same as seen looking in the direction of the feedway of the work and with 35 a transverse section of the presser-foot. Fig. 3 is a horizontal section on line 2 2 of Fig. 2. Fig. 4 is a horizontal section on line 1 1 of Fig. 2. Fig. 5 is a view in reverse of Fig. 2, 40 with some parts in vertical section on line 5 5 of Fig. 6. Fig. 6 is a view in reverse of Fig. 1, with the main shaft in section on line 6 6 of Fig. 5.

A represents the head of the stationary supporting-arm *a*, carrying the presser-bar *b* and the needle *c* in about the same manner as usual.

d is the trimming-cutter-supporting attachment. It is at its upper end attached to the 50 front side of head A by a slideway device *e* and a fastening-screw *f*, so that it may be shifted toward and from the needle *r* later-

ally to the feed-line for varying the width of the margins of the fabric to be overseamed. The cutter-support *d* extends downward below the work-plate (not shown) and carries the stationary cutter *g* thereunder. The reciprocating cutter *h* is carried in a vertical slideway *i* of the support *d*, (see Fig. 1,) being attached to a reciprocating block *j*, fitted in a slideway *k* of said support and connected by pin *l* and rod *m* and strap *m'* with an eccentric *n* on the main shaft *o* for being reciprocated. The lower part of the cutter-support is formed as a chute *p* for discharging the cuttings trimmed off clear of the mechanism; but the cutter attachment is of itself practically the same as shown in my Patent No. 664,277, dated December 18, 1900, to which reference is made for further understanding of the same and need not be more particularly described herein.

My present invention is as follows: For enabling the presser-foot *q* to shift in unison with the cutter attachment, so that the finger *s* employed on said foot for controlling the tension of the thread-loops formed around the trimmed edges of the fabric may have constant uniform relation to the cutters and to the trimmed edges, (for best effects, however, the cutters may be shifted,) I mount said foot on a short shank *t* instead of mounting it directly on the presser-bar, as usual, and connect said shank to the presser-bar by a joint consisting of the yoke *u*, attached to the lower end of the bar, and a pin *v*, that is 80 slideable in the jaws of the yoke and on which the shank *t* is adjustable between the said jaws, where space is provided for shifting the shank to the extent of its desired range 85 of adjustment, and a set-screw *w* is provided for securing the shank in its position on the pin. The pin *v* has at one side of the yoke *u* an arm *x*, capable of turning at one of its ends freely on the pin, but incapable of sliding on it, which arm has a slot *y* in its other end embracing a stud *z*, set in one side of the support *d*, the head of which stud confines the arm *x* between it and said side of the support laterally, but allows the necessary 90 oscillatory movement to accommodate the rising and falling of the presser-foot. Thus at any time it is desired to shift the cutters the presser-foot shifts accordingly, the pin *v* 95

being shifted forward and backward in the yoke u by the arm x , which is shifted by the support d and the stud z . The shank t and the wall 6 of the space between the yoke members u are fitted to bear closely with each other, and thus any rocking motion of the pressure on the pin v that might otherwise occur is prevented.

It is understood that the slot 3 in the presser-foot q is to have suitable width to permit the lateral adjustments of the presser-foot, as specified.

The parts indicated at 4 and 5 represent hook-operating devices; but they form no part of the invention to be claimed and need not be more particularly described.

What I claim as my invention is—

1. In a sewing-machine having an upper and lower trimming-cutter adjustable laterally to the feed-line, the combination with

said cutters, and the stitch-forming elements, of a presser-foot having a thread-loop-controlling finger and being adjustable with the cutters, and means connecting the presser-foot and adjustable cutters whereby both are 25 adjusted simultaneously.

2. The combination with the laterally-adjustable trimming-cutters, and with the presser-bar, of the presser-foot, thread-controlling finger carried by said foot, presser-foot-carrying staff, said staff being laterally adjustable on said bar, and the arm and pin connecting the staff and the cutter-support. 30

Signed at New York city this 10th day of September, 1901.

HERMANN A. KLEMM.
